UNITED STATES PATENT OFFICE.

MONT C. CHADBOURNE, OF DEER PARK, WASHINGTON.

PLANTER.

1,250,559.

Specification of Letters Patent. Patented Dec. 18, 1917.

Application filed August 31, 1915. Serial No. 48,345.

To all whom it may concern:

Be it known that I, MONT C. CHADBOURNE, a citizen of the United States, residing at Deer Park, in the county of Spokane, State 5 of Washington, have invented certain new and useful Improvements in Planters; and I do hereby declare the following to be a full, clear, and exact description of the invention, such as will enable others skilled 10 in the art to which it appertains to make and use the same.

This invention relates to a planter.

An object of the invention resides in the provision of a machine by means of which 15 check row, hill and drill planting may be accomplished.

A further object of the invention resides in so constructing the machine that its 20 operation will be automatic.

A still further object of the invention resides in the provision of a machine which 25 will be comparatively inexpensive to manufacture, easy to operate and of such construction that the liability of the parts becoming inoperative will be practically obviated.

With these and other objects in view, such as will appear as my description progresses, my invention comprises the combination and arrangement of parts as set 30 forth in and falling within the scope of the appended claims.

In the drawing:

Figure 1 is a side elevation of a machine 35 constructed in accordance with my invention;

Fig. 2 is a plan view thereof;

Fig. 3 is an enlarged detail of the portion 40 of the hopper which allows a predetermined quantity of grain to pass therefrom.

Fig. 4 is a fragmental detail showing the means for rotating the bottom of the 45 hopper;

Fig. 5 is a fragmental detail of the actuating arm showing the manner in which it is mounted, and

Fig. 6 is a fragmental detail showing the manner of adjusting the checking arms.

Referring to the drawing by reference 50 characters wherein like parts are indicated by like characters throughout the several views:

In the drawing, I have illustrated a frame which consists of side bars 1. This frame is supported at its forward end by a wheel 2 and at its rear end by a wheel 3

which latter is provided with a supporting shank 4. This shank 4 is mounted in a bearing 5 carried by the side bars 1, is adjustable in the bearing and may be held in any of its adjusted positions by means of a pin which is adapted to pass through any of the openings 6 in the shank. Extending upwardly from the rear of the frame are handles 7. Suitable braces 8 are provided. Extending upwardly from the side bars 1 are supporting members 9 between which a shaft 10 extends. An arm 11 is mounted on this shaft and extends to a point adjacent the wheel 2 where it is provided with a downwardly turned portion 12. This portion 12 is adapted to engage any of a plurality of pins 13 which extend outwardly from the wheel 2. A second arm 14 is mounted on the shaft 10 and extends downwardly below the frame in angular relation to the arm 11. Pivotal secured to this arm 14 is a rod 15 which is at its other end adjustably secured to the arm 11 so that the angular relation of the arms 11 and 14 may be varied. The free end of the arm 11 is normally pulled downwardly by a spring 16 which is secured to one of the members 9. Depending from the side bars 1 are strips 17 on which a hopper is adjustably mounted, which hopper consists of a body 18 of cylindrical formation which is provided with a flange 19 at its lower end, in which flange notches 20 are formed. These notches are adapted to receive upwardly extending lugs 21 on a plate 22 which latter is supported upon a shoe 23. This shoe is held in position by rods 24. Interposed between the lower edge of the hopper body 18 and plate 22 is a false bottom 25, which is provided with a plurality of holes 26 through which seed may drop. A plurality of notches 27 are arranged on the periphery of this false bottom 25 and are adapted to be engaged by a hook arm 28 which is mounted on the lower end of the aforementioned arm 14 and which is pressed into engagement with the periphery of the false bottom by a coil spring 29. The plate 22 is provided with an opening 30 over which the holes 26 pass in their movement. Thus when the arm 14 is actuated, because of the engagement of the arm 11 with one of the pins 13, the hook member 28 will be engaged with one of the notches in the false bottom of the hopper and when the arm is disengaged, thereafter, the spring

16 will move the hook member 28 so that the false bottom will be partially rotated. This movement will bring one of the holes 26 in registration with the opening 30 and 5 the seed will drop therethrough.

In order that the quantity of the seed dropping through the opening 30 may be regulated, I have provided a member 31 which is riveted to the inner face of the 10 body 18 above the opening 30 and is provided with a leveling spring 32. The body of the hopper is held in place upon the plate 22 by coil springs 33.

In order that the machine may be used 15 as a check row planter, I have mounted a frame which consists of an angular bar 36 and a rectilinear bar 37 upon the main frame. Pivotaly mounted on the bar 36, at 38, is an angular lever 39 which is provided with a fork end 40 and has a cam 41 on the opposite end thereof, which may contact with the arm 14. Secured to the lever 39, adjustably, is a coil spring 44 which is, at its other end, secured to one of the side 25 bars 1, at 45. Extending vertically from the ends of the bars 36 are spindles 46, on which rollers 47 are removably mounted. Horizontally extending rollers 48 are mounted on the ends of the bar 37. These rollers 30 47 and 48 are so arranged that a check wire will be guided through the machine, which check wire is prevented from displacement by plates 49.

When the machine is used as a check row 35 planter, the pins 13 will engage the end of the arm 11 and move the hook member 28 into engagement with one of the notches 27 in the false bottom of the hopper. At the same time the arm 14 will engage the cam 41 40 and move the lever 39 upon its pivot until it has passed such position that it will be engaged by the cam 41 and held in such position against the tension of the spring 16. Now as the machine advances one of the end 45 largements on the check wire will engage the fork end 40 of the lever 39 and move the cam 41 out of the path of movement of the arm 14 and allow the spring 16 to actuate the said arm. The actuation of this 50 arm will cause the false bottom of the hopper to be rotated and the seed to be dropped. The intervals at which the seed are dropped will thus be controlled by the check wire.

In order that the machine may be used as 55 a drill planter, I have provided a shaft 50 which is mounted in suitable bearings on the side bars 1 and is provided with a pair of sprockets 51 over which a chain 52 is adapted to pass, which chain is also adapted to 60 pass over sprockets 53 upon the wheel 2. The false bottom 25 of the hopper is provided with a centrally located opening 54 which has channels 55 extending therefrom in which opening a disk 56 is located. This 65 disk is provided with a flat side 57 on which

a spring 58 is secured, which spring is adapted to engage in any one of the channels 55 when the disk 56 is rotated. This disk is secured to a spindle 59 which extends upwardly through the funnel-shaped wall 34 70 and above the hopper. A beveled gear 60 is secured to the upper end of this spindle 59 and meshes with a similar gear 61 upon the shaft 50. Thus when the machine advances, the false bottom of the hopper will be given 75 a continuous motion and the seed will be dropped from the hopper.

It is of course to be understood that when the machine is used as a hill planter the lever 39 will be thrown out of operative position, 80 when it is used as a check row planter the lever will be thrown again into its operative position. Of course when the machine is used either as a hill or check row planter, the chain will be removed from the sprockets 85 51 and 53. When the machine is used as a drill planter, the arm 11 will be thrown out of operative position and the chain 52 will actuate the false bottom of the hopper.

From the foregoing description it will be 90 seen that I have provided a machine which can be used as a hill, check row or drill planter and which may be readily converted from one to the other.

While I have illustrated and described a 95 particular embodiment of my invention, it has merely been for the sake of convenience and I do not wish to be limited to that particular embodiment as it is obvious that numerous changes may be made in the details 100 of construction without departing from the spirit of the invention or exceeding the scope of the appended claims.

What I claim is:—

1. In a planter, the combination with a 105 frame, of a hopper mounted thereon, the said hopper including a false bottom, a wheel for supporting the frame, a shaft supported on the frame, a pair of angularly disposed arms mounted on the shaft, means connecting one of said arms to the false bottom of the hopper, pins on the wheel engageable with the other of the arms and means for varying the angular relationship of the said arms. 110 115

2. In a planter, the combination with a frame, of a hopper mounted thereon, the said hopper including a false bottom, a wheel for supporting the frame, a shaft supported on the frame, a pair of angularly 120 disposed arms mounted on the shaft, means connecting one of said arms to the false bottom of the hopper, pins on the wheel engageable with the other of the arms and means for maintaining the said arms in a 125 predetermined position, the said means being releasable by a check wire.

3. In a planter, the combination with a frame, of a hopper having a rotatable false bottom, a pivotally mounted arm having a 130

hook member thereon adapted to engage the false bottom to rotate the same, means for actuating the said arm, an angular lever mounted on the frame and having a cam on one end and a fork on the other end, the said cam being adapted to engage the said arm and the said fork being adapted to be engaged by the enlargements on a check wire to disengage the cam from the 10 said arm and means for maintaining the cam normally in the path of movement of the arm.

4. In a planter, the combination with a wheel supported frame, of a hopper having 15 a rotatable false bottom, the said false bottom having notches in the edge thereof, a shaft supported upon the frame, an arm mounted on the shaft, a second arm mounted on the shaft and having a hook member on 20 the lower end thereof adapted to engage the

notches in the false bottom, means for maintaining the said arms in various angular relations to each other and means for actuating the arms to rotate the false bottom of the hopper.

5. In a planter, the combination with a wheel supported frame, of a hopper, having 25 a rotatable false bottom, adjustably mounted on the frame, an arm pivotally mounted on the frame and adapted to rotate the said bottom, a second arm pivotally mounted upon the frame for actuating the first mentioned arm and means for varying the angular relation of the said arms.

In testimony whereof, I affix my signature, in the presence of two witnesses.

MONT. C. CHADBOURNE.
